(57) CLAIM

The ornamental design for portable bidet, as shown and described.

DESCRIPTION

FIG. 1 is a front perspective view of a portable bidet showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view of the portable bidet shown with an unclaimed nozzle.

The broken lines shown in the drawings are for illustrative purposes only and form no part of the claimed design.
